STEAM ELECTRIC IRON

Henry Walter Clum, Upper Darby, Pa., assignor
to Philco Corporation, Philadelphia, Pa., a cor-
poration of Pennsylvania

Application May 30, 1944, Serial No. 538,022

4 Claims. (Cl. 38—77)

1

This invention relates to steam irons. In the process of ironing or pressing it is generally desirable first to uniformly dampen the work and then to remove the moisture by the application of heat. Except in the case of irons of the steam electric type, dampening is conventionally done by some direct application of water, such as by sprinkling, for example, and uniformity of dampening is seldom achieved. It is customary in fact, after such application of water to roll the work tightly, cover it, and allow it to stand until the moisture has had an opportunity to spread throughout more or less uniformly, this requiring usually two hours or more, depending upon the nature of the material of which the work is composed.

It is well known that steam is the best medium for uniform application of moisture for ironing purposes, and the steam electric hand iron has combined the dampening and pressing functions in one instrument. Heretofore, such irons have been provided with a single group of steam outlets or jets through which the steam is emitted either continuously or in response to the manipulation of a valve by the operator, and such group of jets has been variously located in accordance with the individual preference of the manufacturer. In some irons, for example, the jets have been located at the front of the soleplate, in others at the sides, and in still others centrally of the soleplate.

It has been found desirable in steam ironing to have the steamed portion of the work subjected immediately to the action of as large an area as possible of the hot soleplate, to thereby remove the moisture and impart the desired ironed finish. Those irons which emit steam solely from the front or side edges of the soleplate usually leave in the work an inadequately dried area when the iron is moved in any direction but straight forward. The hot soleplate of the iron, or a sufficient portion thereof, does not immediately pass over all of the dampened area of the work and thus fails to remove the moisture, with the result that the material is not properly dried and "set." On the other hand, those irons wherein the jets are placed centrally of the soleplate have only localized application of steam and cannot possibly distribute the steam over the entire area swept by the soleplate. With these types of iron the labor of the operator is either greatly increased, or the character of the work is poor.

It is an object of the present invention to provide an improved steam iron in which steam is emitted adjacent the leading edge of the iron

regardless of the direction in which the iron may be moved, whereby the dampened portions of the work are immediately subjected to the action of a substantial area of the hot soleplate.

Another object is to provide a steam iron having a plurality of jet groups from which steam is emitted selectively in accordance with the direction of movement of the iron.

The invention also contemplates the provision of a steam iron wherein the foregoing operation is accomplished without special manipulation on the part of the operator.

A further object is to provide an iron having a plurality of steam outlet apertures or jet groups which are individually operable to emit steam in response to forces exerted in the act of moving the iron.

Still further, an object of the invention is to provide a steam iron of the aforesaid character having the added characteristics of structural simplicity, rugged design, and adaptability for economical mass production.

In the attached drawings:

Figure 1 is a perspective view of a steam electric iron embodying the invention;

Figure 2 is a longitudinal vertical sectional view of the iron on the line 2—2 of Figure 1;

Figure 3 is a sectional view taken on the line 3—3 of Figure 2;

Figure 4 is a top plan view of the soleplate detached from the rest of the iron;

Figures 5, 6, 7 and 8 are diagrammatic views of the soleplate, each illustrating a separate jet group and its effective operational characteristics; and

Figure 9 is a fragmentary view of a modification of the invention.

Referring particularly to Figures 1 and 2 of the drawings, the iron comprises generally a base member or soleplate 10, a cover 11 suitably secured to the soleplate, and a handle 12 carried by said cover.

More particularly, the soleplate 10, as illustrated in Figure 4, is of conventional streamlined configuration and is provided with four groups of outlet apertures or jet groups 16, 17, 18 and 19 which together substantially surround the major area of the soleplate. Each jet group comprises a plurality of steam discharge apertures or jets 20 which communicate with channels 21, 22, 23 and 24, respectively, formed in the upper surface 25 of said soleplate. It should be understood that, while it is considered preferable to have four jet groups this number may be increased or decreased, as desired.

Each of said channels 21, 22, 23 and 24 communicates through channels 28, 29, 30 and 31, respectively, with upwardly extending ports or passages 32, 33, 34 and 35, formed in a hollow upwardly extending portion 36 of soleplate 10.

The hollow interior of the extension 36 forms a steam chamber 39 (see Figure 4) into which water is admitted from a reservoir 40 (Figure 2), through a passage 41 formed in a raised boss portion 42 of said soleplate 10. The reservoir 40 is preferably formed integrally with the cover 11 and in the present instance entirely encircles the extension 36. A depressed portion 43 of the bottom wall 44 of the reservoir 40 is adapted to fit into a recess 46 in the upper surface of boss 42, and is provided with an opening 47 through which is passed a valve seat fitting 48, said fitting having an aperture 49 therethrough which communicates with the passage 41 and establishes communication between the passage and the reservoir 40. The fitting is threaded into the boss 42 and is of a character to firmly secure the reservoir to the soleplate. A gasket is provided between the head of the fitting 48 and the opposed surface of the depression 43 to make the connection watertight.

Regulation of the quantity of water to pass through the aperture 49 and passage 41 to steam chamber 39 is effected in the illustrated embodiment, through the medium of a needle valve 50 having threaded connection with a raised boss 51 on the cover 11, said boss being located directly over the valve seat. The valve is provided with a knob 52 for regulating the rate of flow of the water to the chamber, or for completely shutting off the water supply to the steam chamber 39 when it is desired to iron dry, or during periods when the reservoir is being filled. A filler opening 53 is provided in the cover, which opening is normally closed by a removable plug 56.

The soleplate 10 is provided in the present instance with an armored electrical heater element 57 of well-known construction and comprising an outer metallic tube 58 having a resistance element 59 supported in concentric spaced relation thereto by means of a suitable heat-conducting electrical insulating material 60. Electrical energy for heating the iron is supplied through a cord 61 provided with conventional means for connection to an electrical outlet (not shown). This cord comprises conductors 62 one of which is connected to an end of resistance element 59 and the other to one side of a manually adjustable thermostatic switch 63 mounted in recess 64 in cover 11, the said element 59 and switch 63 being connected together to form a series circuit under control of the latter. A knob 65 is provided for manual adjustment of the thermostat.

A cover plate 66, suitably secured to the soleplate 10, as by screws 67, encloses the channels 21, 22, 23 and 24, and 28, 29, 30 and 31 and forms therewith conduits for conducting the steam to the several jet groups 16, 17, 18 and 19, individually, as determined by a valve 13, hereinafter more fully described.

The steam chamber is preferably of the "flash" type; i. e., water from the reservoir flows through passage 41 into contact with the heated bottom wall 68 of the chamber and is immediately converted into steam.

The upper edge of the chamber walls comprises a valve seat 69 for a hollow substantially spherical valve member 70 having its bottom portion cut away, as at 71, to permit steam from the steam chamber to enter the interior of the valve. A cap 75

member 72 having an opening 73 (the surface of which is shaped to fit the spherical surface of the valve and to provide a snug fit therewith) is secured to the top of the extension 36, as by screws 74. Radial grooves 77 in the lower surface of the cap member 72 register with radial grooves 78 in the top surface of extension 36 to provide radial extensions of the passages 32, 33, 34 and 35. Valve member 70 normally interrupts communication between these radial extensions and steam chamber 39, but is provided with horizontally slotted ports 79, 80, 81 and 82 which are arranged to register respectively with the inner ends of the aforesaid extensions when the valve is turned in the manner now to be explained.

The handle 12, which comprises forward and rearward standards, 83 and 84, respectively, and an intermediate grip portion 85, is slidably connected to the top surface of cover 11. To this end, the forward standard 83 is provided with a depending stub shaft 86 which extends through an opening 87 of larger diameter than the shaft to permit limited lateral movement of the handle in any direction relative to the cover. Larger washers 88 are carried by shaft 86 on each side of the cover to prevent angular displacement of the handle relative to the cover, and provide bearing surfaces for the sliding movements. The handle is connected with valve 13 through a ball and sleeve joint 89 which includes a ball 90 on the top of valve member 70, and a sleeve 91 secured to the lower end of shaft 86 and into which the ball snugly fits. To prevent relative rotation of the handle and valve, the ball is provided with a pair 35 of radial pins 92 which fit into slots 93 in opposite sides of the sleeve, said slots being sufficient in length to permit relative vertical movement of the pins and the sleeve when the handle is moved. A pair of opposed springs 94 are attached respectively to the ends of pins 92 and to the walls of reservoir 40, and normally resiliently retain the valve in a central position, as illustrated.

To prevent horizontal rotational movement of the handle about the axis of the shaft 86, while still permitting the aforesaid lateral movements, the rear standard 84 of the handle is provided with a short depending lug 95 which extends through a slot 96 in cover 11.

The rearward standard of the handle is also provided with an upwardly projecting portion 97 which cooperates with the heel 98 of the soleplate in providing a stable support for the iron when rested in an upright rest position upon a horizontal surface, as indicated by the broken line 99. When in this position of rest, the level of the water in reservoir 40 will be below the outlet aperture 49 of the valve seat 48, thereby precluding entrance of water into the steam chamber 39.

Operation of the iron is as follows:

Assume reservoir 40 to be substantially filled with water, needle valve 50 set to the desired position, and thermostat 63 set for the degree of heating required for the particular material to be pressed. Handle 12 is grasped by the operator and the iron is moved over the material by applying force to the handle in the direction desired. This force first effects a slight movement of the handle with relation to the body of the iron in the direction of applied force, thereby turning the valve 13 in a manner and to an extent to establish communication between the steam chamber and one or other of the jet groups, depending upon the direction of force.

More specifically, let it be assumed that the

force upon the handle is in the forward direction. It will be seen by reference to Figure 2 that the handle will move forwardly with relation to cover 11 until shaft 88 engages the wall of opening 87, this movement causing rotation of valve member 70 sufficient to register port 79 with the radial extension of passage 32, thus effecting communication between steam chamber 39 and the forward discharge apertures or jet group 16 through channels 28 and 21. Steam generated in the chamber will then be emitted from jet group 16 so that the steamed area of the work may be immediately subjected to action of a major portion of the hot soleplate as the iron is advanced. In like manner a rearward movement of the iron brings the port 81 of the valve into registration with the radial extension of passage 34 and permits steam to flow from steam chamber 39 through passage 30 and channel 23 to the jets 20 of the rearward jet group 18. Side-wise movement away from the viewer (as the iron is seen in Figure 2) rotates valve 70 to bring port 80 into registration with the radial extension of passage 33 and will effect communication between the steam chamber 39 and jet group 17. Similarly, movement of the iron in an opposite sidewise direction brings the port 82 into registration with the radial extension of passage 35 and thereby permits steam to flow through passage 31 and channel 24 to the jets 20 of group 19.

As more clearly illustrated in the diagrammatic Figures 5, 6, 7 and 8, if the iron is moved forwardly in any direction encompassed by angle A (Figure 5), the jet group 16 will be the only group emitting steam, and, as indicated by lines A¹, during such movement the steamed area will be immediately overrun by a substantial portion of the hot solepath. Thus, if the iron is moved in the direction indicated by the arrow heads on line A¹, the area of the soleplate between that line and its associated line A¹ will immediately overrun the area of the work subjected to steam from jet group 16, which area is indicated by the shaded portion A¹¹. Similarly, when the iron is moved in any direction encompassed by angle B (Figure 6) jet group 17 will be the only group emitting steam, and parallel lines B¹ indicate that portion of the hot soleplate which overruns the area steamed by this group. As indicated by Figures 7 and 8, a corresponding condition exists with jet group 18, angle C, and lines C¹; and with jet group 19, angle D, and lines D¹.

Thus, the invention provides a steam iron from which steam is emitted in effect only from the leading edge of the iron irrespective of the direction in which it may be moved, whereby the area dampened by the steam is immediately subject to the pressing and drying action of a substantial portion of the total area of the hot soleplate. In the present instance, the emission of steam is automatically responsive to forces applied in manipulating the iron.

Under certain conditions, such, for example, as when it is desired to iron pleats, gathers and other such portions of the garment being pressed, it is particularly advantageous to emit steam from the toe only of the iron. For this purpose, and with reference to Figure 9, the above described device may be modified as follows: The slot 100 corresponding to slot 86 in the afore-described embodiment is provided with an offset portion 101 and a spring retainer 102. When it is desired to have steam emit only from the forward jet group, the body of the iron is held

10 while the handle is moved forwardly until the slot 100 is registered with the offset portion 101, whereupon the spring retainer 102 will be depressed by the lug 85 so that the handle may move into the offset portion 101. The lug 85 may be released manually by depressing the retainer directly or by exerting sufficient force through the handle in a clockwise direction against the retainer to cause it to move to its depressed position so as to allow lug 85 to return to slot 100.

15 While a specific mechanism has been illustrated to accomplish the objects set forth it is evident that variations thereof are possible without departing from the invention.

I claim:

1. A steam iron comprising a soleplate having a front jet group, opposite side jet groups, and a rear jet group, means for heating said soleplate, a source of steam, valve means for directing steam from said source to the said jet groups, selectively, a member for transmitting motion to the iron in performance of the ironing function, said member having lost motion with respect to the sole plate so that each movement of the iron so transmitted is preceded by a movement of the member in substantially the same direction and with respect to said plate, and means for operatively associating the member with the valve means so that each said preceding movement of the member actuates the valve means to direct steam to a predetermined jet group, said member being movable from a neutral position, wherein the valve prevents passage of steam to any of said groups, into each of a plurality of open positions admitting steam respectively to said groups, and also from each of said open positions directly to the open positions immediately adjoining.
2. A steam iron comprising a soleplate having a front jet group, opposite side jet groups, and a rear jet group, means for heating said soleplate, a source of steam connected to said jet groups, valve means interposed between said jet groups and said source for directing steam from the source to said groups, selectively, a member for transmitting motion to the iron in performance of the ironing function, said member having lost motion with respect to the sole plate so that each movement of the iron so transmitted is preceded by a movement of the member in substantially the same direction and with respect to said plate, and means for operatively connecting the member with the valve means so that each said preceding movement of the member will actuate the valve means to direct steam to the jet group toward which the movement of the member occurs, said member being movable from a neutral position, wherein the valve prevents passage of steam to any of said groups, into each of a plurality of open positions admitting steam respectively to said groups, and also from each of said open positions directly to the open positions immediately adjoining.
3. A steam iron including a water supply reservoir, a steam generating chamber connected to said reservoir, a soleplate having a plurality of jet groups jointly substantially surrounding said soleplate, means connecting said jet groups to said chamber, and unitary valve means interposed between said groups and said chamber for selectively controlling passage of steam to said groups, a member for transmitting motion to the iron in performance of the ironing function, said member having lost motion with respect to the

sole plate so that each movement of the iron so transmitted is preceded by a movement of the member substantially in the same direction and with respect to said plate, and means for operatively connecting the member with the valve means so that each said preceding movement of the member will actuate the valve unit to direct steam to the jet group toward which the movement of the member occurs, said valve unit having a universal mounting permitting direct movement thereof between operative positions wherein steam is admitted respectively to said jet groups, and between each of said positions and a neutral position wherein steam is excluded from all of said jets.

4. A steam iron comprising a soleplate having four separate jet groups for emitting steam, a cover overlying and secured to said soleplate, means for heating said soleplate, a steam generator carried by said soleplate, a water supply reservoir carried by said cover, means including an adjustable valve for supplying water from said reservoir to the steam generator, means connecting said jet groups to said generator, valve means interposed between said jet groups and the generator, a handle mounted on the cover, said han-

10 dle being free for limited movement with respect to the cover in directions generally parallel to the plane of said sole plate and being connected to the valve means by such construction that said movements of the handle relative to said cover will actuate the valve means in a manner to direct steam to said jet groups selectively in accordance with the direction of movement of said iron, resulting from pressure applied thereto by way of said handle.
